US00D656852S

(12) **United States Design Patent**
Granius et al.

(10) **Patent No.:** US D656,852 S
(45) **Date of Patent:** ** Apr. 3, 2012

(54) **WETNESS INDICATOR**

(75) Inventors: **Marty J. Granius**, Menasha, WI (US);
Paula K. DeBruin, Sherwood, WI (US);
Joy Patricia Bauman, Neenah, WI (US);
Marcille Faye Ruman, Oshkosh, WI (US)

(73) Assignee: **Kimberly-Clark Worldwide, Inc.**,
Neenah, WI (US)

(**) Term: **14 Years**

(21) Appl. No.: **29/367,398**

(22) Filed: **Aug. 6, 2010**

(51) **LOC (9) Cl.** 10-04

(52) **U.S. Cl.** D10/101

(58) **Field of Classification Search** D10/56,
D10/101; D24/124, 126; 374/162; 422/401;
604/360, 361

(57) **CLAIM**

The ornamental design for a wetness indicator, as shown and described.

DESCRIPTION

FIG. 1 is a full perspective view of a first embodiment of a wetness indicator on an absorbent article showing the design; FIG. 2 is a front view of wetness indicator of FIG. 1; FIG. 3 is a rear view of the absorbent article of FIG. 1; FIG. 4 is a top view of the absorbent article of FIG. 1; FIG. 5 is a bottom view of the absorbent article of FIG. 1; FIG. 6 is a left side view of the absorbent article of FIG. 1; FIG. 7 is a right side view of the absorbent article of FIG. 1; FIG. 8 is a front perspective view of the wetness indicator on a substrate; FIG. 9 is another embodiment of a wetness indicator on a substrate; FIG. 10 is another embodiment of a wetness indicator on a substrate; and, FIG. 11 is another embodiment of a wetness indicator on a substrate. The claimed design comprises the elements shown in solid lines, the absorbent article shown in dotted lines in FIGS. 1 through 7 forming no part of the claimed design.
